UNITED STATES PATENT OFFICE.

PHILIP X. RICE, OF STATE COLLEGE, PENNSYLVANIA, ASSIGNOR TO GENERAL RAILWAY SIGNAL COMPANY, OF ROCHESTER, NEW YORK.

ALTERNATING-CURRENT DYNAMIC INDICATION SYSTEM.

Application filed March 10, 1923. Serial No. 624,265.

This invention relates to interlocking systems, and particularly to means for obtaining a reliable indication as to the position of a traffic controlling device.

In electric interlocking systems commonly used, at least two particular types of electrical indication have been used, namely:—
(1) systems in which certain circuits are closed which include a constant supply of energy when an indication is to be given; and (2) systems transmitting energy of a distinctive character in a closed circuit momentarily, this energy being derived from the motor of the traffic controlling device with which it is associated (such as a switch machine, semaphore signal or derail) as the motor decelerates at the completion of an operating cycle. This latter type of system is commercially known as a dynamic indication system, and it is to this latter type of system that the present invention particularly relates.

Dynamic indication has been successfully employed for operating switch machines and derails, which must be positively driven to the normal and also to the reverse position, and wherein the dynamic indication current is generated after the motor has operated the traffic controlling device into one or the other position as conditions may require. In this application of the dynamic indication principle, the indication current is derived by the inertia of the motor and its associated parts after it has completed the movement of the traffic controlling device. In applying the dynamic indication principle to manually controllable electrically operated signals, which are only moved to the clear position by a motor, the indication current is generated by the motor when it is being driven backwards when the signal gravitates to the zero degree or danger position. Similarly, this same principle of obtaining an indication current on the dynamic principle has been applied to signals which are automatically operated, but which may be moved to the danger position manually. In this type of system, a suitable energy storing device, such as a spring, is provided, which is adapted to operate the signal motor providing the signal is already assuming the normal danger position and the lever is in the indication position.

In each of the systems above mentioned in which the dynamic indication principle

has been applied commercially, a commutator motor has been used, this motor being operated either by direct or alternating current when used as a motor depending on its construction and the kind of energy available, and functioning as a direct current generator when used to generate an indication current. In the present invention, it is contemplated to apply this dynamic indication principle to traffic controlling devices, such as heretofore mentioned, by employing an alternating current motor, either of the well-known induction type which do not require commutators or of the commutator type for driving such traffic controlling device, and also for generating an alternating current of distinctive character at the time a flow of an indication current is proper.

More specifically, it is proposed to provide an induction motor, either of the polyphase or splitphase type for actuating the traffic controlling device to the proper position, and to energize one of the windings of this motor with an alternating exciting current, which in turn causes the generation of an alternating current in another phase of such motor. This generated current being used to control a suitable electro-responsive device, which is adapted to give a visual indication, is adapted to unlock a lever, or is adapted to carry out both of these functions. The several constants of a system of this type are preferably so chosen that the dynamic indication current will have a distinctive phase relation with respect to any current that could possibly be obtained by unauthorized crosses of wires, or the like.

Other objects, purposes and characteristic features of the invention will appear as the description thereof progresses.

In describing the invention in detail, reference will be made to the accompanying drawing in which the present invention has been applied to give an indication in connection with a lever for operating a two-position signal. In illustrating the invention, the various parts have been shown in a manner to make it easy to understand the invention, rather than with the view of showing the particular construction preferably employed in practice.

Structure.—Referring to the drawing, a trackway comprising rails 1 has been illustrated adjacent to which there is shown a signal S, which is manually operated from

a distant tower which has been conventionally illustrated by the dotted rectangle. This signal is presumed to protect a certain conflicting route, which has not been shown in the drawing. Certain of the most essential elements of the signal S have been conventionally illustrated adjacent thereto, so as to facilitate the description of the present invention without referring to certain other parts, which are well-known to those skilled in this particular art, and have been omitted.

In the interlocking tower is provided a manually operable lever L, which with its associated parts comprises a portion of a well-known and commercially used dynamic indication interlocking system, and therefore will not be described in detail. It may, however, be stated that the coils 4 and armature 5 are parts of an indication magnet IM, which in connection with the detent 6 is adapted to release the lock dog 7 from the locking shoulder 8 of the lever L when this lever is being operated from the reverse position toward the normal position, in which it has been shown. The lever is locked in the half normal position (as shown by the dot and dash line representing the contact block), showing the contact block in engagement of this locking shoulder 8 with the lock dog 7, this locking of the lever L in the half normal position persisting until an indication current is received by the coils 4 of the indication magnet IM. A momentary flow of current through these coils 4, with the lever in the half normal position, causes the armature 5 of the indication magnet to be attracted to move the detent 6 from under the lock dog 7 whereby the spring 9 moves the lock dog 7 to its ineffective position, thus enabling the tower attendant to move the lever L to the full normal position, and in turn unlock certain other conflicting levers, such unlocking of conflicting levers being effected by the movement of the roller 10 associated with the tappet bar 11 to the extreme lower position, as shown.

It should be noted that movement of the lever L toward the left, that is, toward the reverse position does not cause it to be effectively locked when reaching the half reverse position, although the righthand end of the lock dog 7 is moved upward and retained there temporarily by the detent 6. As the lever is moved toward the left, the projection 12 rocks the unlocking cam 13 which in turn strikes the tail piece of the detent 6, thereby unlocking this lever. That is, the lever L is locked in both, the half normal and the half reverse position, but upon movement of the lever toward the reverse position, mechanical unlocking takes place regardless of the condition of the distant traffic controlling device, that is, the signal S in the particular arrangement shown; whereas move-

ment of the lever toward the right, that is, toward the normal position, does not permit such mechanical unlocking, the unlocking in this instance being accomplished by the energization of the indication magnet IM.

In the tower is also provided an indication relay IR. This indication relay IR is preferably of the two-element type, and may be of either the dynamometer or the induction type. This relay has been illustrated conventionally, as shown, by the local winding 14 and the operating winding 15. If an induction type of relay is used, the local winding 14 will be constructed so as to be highly inductive, thereby causing the flux produced by the local winding to lag almost 90 electrical degrees behind the voltage producing this flux, so that the flow of a power current flowing into the operating winding 15 through the wire 52 will produce an effective torque to move the contacts 16 and 17 toward the right for purposes more clearly explained hereinafter. On the other hand, if a dynamometer type of relay is used the local winding is constructed to be highly resistive for the same reason, that is, so that power current will produce an effective torque on the relay in one direction and current leading or lagging substantially 180 electrical degrees will produce a torque in the opposite direction. A transformer T is also provided in or near the signal tower.

The signal S, among other things, includes the semaphore 20 adapted to be moved to the clear or 45 degree position, as shown by dotted lines, by a suitable motor M conventionally shown as comprising a rotor 21, a highly resistive winding 22 and a highly reactive winding 23, which in practice are displaced substantially 90 electrical degrees, so that no voltage can be induced from one winding into the other except by the rotation of the rotor 21. Associated with this signal S and operated by the semaphore shaft are circuit controllers 25, 26 and SC. The circuit controller 25 is adapted to close a circuit for the hold-clear device HC shown, and closes a circuit only when the semaphore blade 20 is in the 45 degree or clear position. The circuit controller 26 completes a circuit for operating the signal motor M to the clear position, and is closed for all positions of the semaphore blade 20 between the zero and, say, the 43 degree position.

The circuit controller SC is of a peculiar type and connects the resistive winding in multiple with the inductive or reactive winding at all times both in the upward and downward movement of the semaphore, except while the semaphore is moving, say, from the 15 degree to the 5 degree position during its downward movement. During this portion of the downward movement of the semaphore blade 20 (that is, between the 15 and 5 degree positions), a circuit is com-

pleted for energizing the resistive winding of the motor M. This circuit controller comprises a device which for convenience has been illustrated as a disc 27 of insulating material 5 operatively connected to the semaphore blade, and having a projecting extension or lug 28. Suitably supported upon the insulating block 29 is a bracket 30, having its end bent to form a sleeve for pivotally supporting a switch operator. This switch operator has been conventionally shown as comprising a triangular plate 31 provided with three pins 32, 33 and 34 respectively, the pin 32 serving as a support for the triangular plate and being pivotally supported in the sleeve of the bracket 30. To the bracket 30 and adjacent the end where it is supported is riveted a contact spring 35, which is adapted to contact with one or the other of two stationary contacts, conventionally shown by arrows.

By looking at the conventional showing of this circuit controller SC, it will be noted that movement of the insulating disc 27 from the normal danger position of the semaphore shown, to the 45 degree or clear position (shown by dotted lines), will cause the extension 28 to engage the pin 34, thereby tilting the triangular plate 31 of the switch operator toward the right without in any way affecting the spring contact 35. As soon as the extension 28 leaves the pin 34, the triangular plate is returned back to its normal position shown, by gravity, or by a suitable spring (not shown). Upon return of the semaphore 20 and the insulating disc 27 to the normal position, the extension 28 of this disc will again engage the pin 34 of the switch operator. In this instance, the triangular plate 31 will be tilted downward, thereby causing the pin 33 to engage the contact spring 35 and move this contact spring toward the left causing it to interrupt the circuit normally closed by this spring contact and complete another circuit. As the insulating disc 27 reaches the 5 degree position, the plate 31 will again be free to move because the pin 34 is no longer engaged by the extension 28, thus allowing the switch operator to assume the normal position shown, due to the tension of the spring contact 35 exerted upon the pin 33.

The hold-clear device HC heretofore referred to may take any one of a variety of forms well-known in the art of railway signaling, and comprises means which if energized will hold the semaphore of the signal in an elevated position against the action of gravity, and usually comprises a suitable type of detent or brake device and has for convenience been illustrated by the coils 37.

Operation.—In the particular embodiment of the invention illustrated, the local winding 14 of the indication relay IR is normally energized by the transformer T through a

circuit comprising the secondary winding 40 of the transformer T, wires 41 and 42, local winding 14 of the indication relay IR, wire 43 back to the secondary winding 40.

Let us assume now that the tower attendant wishes to allow a train to pass the signal S, and therefore moves the lever L toward the reverse or lefthand position, as shown in the drawing. As this lever is moved toward the left, the righthand end of the lock dog 7 will be cammed upward after the shoulder 8 has moved by this end, thereby causing the detent 6 to engage the lock dog 7 and hold it in this locked position. Further movement of the lever L toward the left at first seems impossible on account of lug 12 engaging the right hand end of the lock dog 7. This, however, is not the case, because the lug 12 engages the unlocking cam 13 which in turn engages the tail piece of the detent 6 and trips the lock dog, thereby again unlocking the lever and permitting it to be moved to the extreme lefthand or full reverse position.

With the lever in the reverse position, an operating circuit for the motor M is completed which may be traced as follows:—Beginning at the secondary winding 40 of the transformer T, wires 41, 42 and 56, contacts 57, 3 and 58 of the signal lever L, wires 53 and 54, circuit controller 26, wire 55; a multiple circuit comprising wire 63, contact spring 35, wire 62, winding 22 of the motor and in multiple therewith comprising wire 59, inductive reactance 60, wire 61, and winding 23 of the motor M; and from this multiple circuit wires 45 and 46, contact 17 of the indication relay IR, wire 47 back to the secondary winding 40 of the transformer T. The completion of this circuit causes current to flow through the windings of the splitphase motor M; and on account of the resistive feature of one of the windings and the reactive feature of the other winding, the current flowing through these two windings will be considerably displaced in phase, and will cause the motor to operate and through suitable gearing (not shown) actuate the semaphore 20 to the 45 degree or clear position.

During this movement of the semaphore 20, when it reaches the 43 degree position, the circuit controller 26 will interrupt the energizing circuit for the motor M. The inertia of the motor will, however, operate the semaphore to the 45 degree position, which will cause the circuit controller 25 to complete the following circuit:—Beginning at the secondary winding 40 of the transformer T, wires 41, 42 and 56, contacts 57, 3 and 58 of the signal lever L, wires 53 and 64, circuit controller 25, wire 65, coils 37 of the hold-clear device HC, wires 66 and 46, contact 17 of the indication relay IR, wire 47 back to the secondary winding of

the transformer T. The completion of this circuit energizes the hold-clear coils 37 and causes the hold-clear device HC to maintain the semaphore 20 and its associated parts in the clear or 45 degree position. During this movement of the semaphore from the danger to the clear position, the spring switch arm 35 was not actuated for reasons heretofore given in the brief description of the operation of the circuit controller SC.

Let us assume now that the tower attendant wishes to again return the signal S to its normal danger indicating position, possibly because the train heretofore mentioned has passed the signal S, and another train is about to take a conflicting route, such as a siding or a crossing as well understood by those skilled in the art. To do this, he will push the lever L toward the right until it has reached the half normal or indication position, as shown by the dot and dash position of the contact block 3. In this position of the lever L, the shoulder 8 engages the righthand end of the lock dog 7, thereby preventing further movement of the lever toward the right, that is, locking the lever in this position as far as the movement toward the normal position is concerned. This movement of the lever interrupts the circuit for the hold-clear device HC of the signal S, thereby allowing this signal to gravitate toward the zero degree or danger position. When the signal reaches the 15 degree position on its downward movement, the extension 28 of the disk 27 engages the pin 34 of the switch operator, moving the plate 31 in a counter-clockwise direction about the pivot pin 32, thereby causing the spring switch arm 35 to move toward the left in contact with the stationary contact 68, which completes an exciting or field circuit for the winding 22 of the motor M.

This circuit may be traced from the secondary winding of the transformer T, wires 41, 42 and 69, stationary contact 68, spring contact 35, wire 62, winding 22 of the motor M, wires 45 and 46, contact 17 of the indication relay IR, wire 47 back to the secondary winding of the transformer T. The completion of this circuit causes a current to flow in this circuit, which is substantially in phase with the voltage of the transformer T, this being due to the fact that the winding 22 is highly resistive.

It should be noted that the motor was free to rotate due to the action of gravity acting on the semaphore 20 and has reached a fairly high speed, somewhere in the neighborhood of synchronous speed of the motor, by the time it reaches the 15 degree position just referred to. With the motor running at a high speed and the resistive winding energized from the transformer T, as just explained, a voltage will be induced in the other winding 23 of the motor M which

voltage lags substantially 180 degrees behind the voltage of the secondary winding of the transformer T. Since the operating winding 15 of the indication relay IR is resistive rather than reactive, the current flowing due to this voltage generated dynamically in the winding 61 will cause the current flowing in the indication circuit including this winding to likewise lag substantially 180 degrees behind the voltage impressed on the local winding 14.

This indication circuit may be traced as follows:—Beginning at the winding 23 of the motor M, wire 45, common return wire 46, contact 17 of the indication relay IR, wires 47, 43 and 48, contacts 49, 3 and 50 of the switch lever L, wire 51, operating winding 15 of the indication relay IR, wires 52, 53 and 54, circuit controller 26, wires 55 and 59, inductive reactance 60, wire 61 back to the winding 23 of the motor M. The flow of this current which is substantially in phase opposition with the voltage of the transformer, as far as the winding 15 is concerned but flows in the same relative direction in the wire 53 as does the current for operating the motor M, causes the relay to be energized in a manner to move the contacts 16 and 17 toward the left.

The movement of the contact 17 toward the left continues to complete the common return circuit heretofore mentioned; and the movement of the contact 16 toward the left completes an energizing circuit for the indication magnet IM, which may be traced as follows:—Beginning at the secondary winding 40 of the transformer T, wires 41 and 70, contact 16 of the indication relay IR, wire 71, coils 4 of the indication magnet IM, wire 72 back to the secondary winding 40 of the transformer T. The completion of this circuit energizes the indication magnet IM, thereby causing the armature 5 to move upward and trip the detent 6 to release the lock dog 7 and allow the spring 9 to move the lock dog out of engagement with the shoulder 8, thus allowing movement of the lever L to the full normal position, and in turn allowing it to unlock other conflicting similar levers (not shown for simplicity) for reasons heretofore mentioned.

It should be noted that the indication relay IR was actuated toward the left when the dynamic indication current, which lags substantially 180 degrees behind the voltage of the transformer T, was received. Consequently, if for any reason unauthorized current should be applied to the wire 53 for instance while the lever L is in the full normal position as shown, such current may tend to operate the motor M. It should, however, be noted that a circuit of fairly low resistance, and low impedance, through the operating winding 15 of the indication

relay IR is present. This latter shunting circuit would to a large extent prevent any considerable amount of current from flowing in the winding of the motor M, and the 5 motor would probably not be operated at all by this small current. On the other hand, the flow of this current through the operating winding 15 of the relay IR would cause this relay to be actuated in the reverse 10 direction from that in which it was actuated by the dynamic indication current, because this unauthorized current, which is presumed to have come from the secondary winding 40 of the transformer T, is substantially 15 in phase with a voltage of this transformer; whereas the indication current, as heretofore explained, is substantially 180 degrees out of phase with the voltage of this transformer. Consequently, the 20 indication relay IR will now be actuated in the reverse direction, and will cause the contacts 16 and 17 to be moved to the right, and be latched in this position by the hooks 25 74 and 75 respectively. The hook 74 maintains the contact 17 in this latter position, whereas the hook 75 does both, hold the contact 16 in the extreme righthand position and complete a circuit for the danger lamp R, which can be readily traced in the drawing. 30

It should be noted that this movement of the indication relay IR toward the right, not only causes the contact 17 to be latched by the hook 74, but also causes an interruption 35 at this point in the common return wire 46. Thus, the presence of unauthorized current due to crosses and the like, will no longer be permitted to flow through the winding of the motor M, since the common 40 return circuit is permanently interrupted. The indication relay IR is in practice housed in a suitable casing (not shown), which is preferably provided with glass walls and is sealed so that the tower attendant cannot 45 tamper with the relay mechanism. If desired, suitable tripping mechanism may be provided to allow the attendant to withdraw the hooks 74 and 75, to again allow the relay to assume its deenergized position after 50 having once been operated toward the right. This construction permits the attendant to release the hooks, thereby allowing the main return circuit to again be completed, but does not allow him to forcibly hold the 55 common return circuit intact.

The dynamic indication system embodying the present invention thus affords the generation of an alternating current having a distinctive phase relation from that obtainable from the transformer T operating the signal in connection with which the indication system has been shown. This conclusion is based on the assumption of a cross 60 between the main motor feed wire 53 and a wire connected directly to the wire 41

or a connection to the secondary winding 40 of the transformer T, due to a cross of some kind or other. Obviously, if the common return wire 46 were connected to the wire 41 of the transformer, and the other 70 side of this transformer winding were connected to the wire 53, the indication relay IR would not be actuated to the right to interrupt the common return circuit on account of such a cross. A complicated cross 75 of this character is, however, highly improbable, and possibly would never occur in practice.

Although in the particular system illustrated an induction motor has been shown 80 for operating a distant traffic controlling device, and for in turn generating an alternating current of the proper phase relation with respect to the source of supply for indicating that the traffic controlling device has reached 85 a certain position, this principle of dynamic indication may also be applied to systems employing alternating current commutator motors. If a commutator type of motor is used, the field winding may be energized by 90 alternating current at the time an indication is proper, whereby an alternating current will be commutated which is of the same frequency as that flowing in the field winding. Obviously, the same general circuit arrangement 95 will also be satisfactory in systems employing commutator motors.

It should be noted that this dynamic indication system also serves to snub or retard the motor as the signal gravitates from the 100 15 degree to the 5 degree position. Obviously, if desired, this snubbing or dynamic braking may be used independently of dynamic indication in systems where indications are not necessary, or are provided in 105 some other way. Also, it should be noted that if the speed of the motor is above synchronous speed, there will not only be an indication current generated, but there will also be a regenerative current flowing 110 in the exciting circuit, which will feed energy back into the secondary winding 40 of the transformer T.

Having thus shown and described one specific embodiment of the invention, it is desired to be understood that this same dynamic indication principle may be applied to switch machine motors, derail, operating 115 motors, and the like, and that other types of polyphase induction motors may be employed, by making various changes, modifications and adaptations, within the scope of this invention and without departing from the idea of means underlying the same.

What is desired to be secured by Letters 120 Patent of the United States, is:—

1. In a dynamic indication system, the combination with a polyphase induction motor having a rotor and a stator provided with only two windings displaced substan- 125 130

tially ninety electrical degrees; and of means for giving an indication when said motor has completed a certain cycle of operation, said means including an electro-responsive device operated by current generated in one of said windings due to an exciting current in the other of said windings and the action of the said rotor when rotating.

5 2. In an interlocking system for railways, the combination with a lever of a mechanically interlocked group of levers, a lock for said lever, electro-responsive means for releasing said lock, a distant traffic controlling device including an induction motor having two field windings and a rotor of the non-commutating type controlled by said lever, and a circuit including one of said windings for actuating said electro-responsive device when said motor has completed a certain 10 cycle of operation.

15 3. An interlocking system for railroads comprising, a lever of a mechanically interlocked group of levers, a distant traffic controlling device, an induction motor for operating said traffic controlling device and having two windings and a rotor of the non-commutating type, and means for connecting one of said windings to a source of alternating current while the other winding is connected to said electro-responsive device when said motor has substantially 20 completed its cycle of operation.

25 4. In an interlocking system for railroads, the combination with a remote electrically controlled traffic controlling device controllable by a lever of a group of mechanically interlocked levers through a main wire and a common return wire; said lever having a normal, a reverse and an indication position; 30 a source of alternating current having one terminal connected to said common return wire, a polarized alternating current indicating device connected to said common return wire and also connected to said main wire when said lever is in the indication and in the normal position, said traffic controlling device including a motor operable by alternating current, and means including said motor for dynamically generating an alternating indication current flowing in said main wire and said common return wire through said indicating device when said motor has completed a predetermined cycle of operation, which current has substantially 35 the same phase relation with respect to said source as the power current flowing from said source to said motor through said main wire when said motor is energized, whereby a cross between said source and said main wire while said main wire is connected to said indicating device will establish a current to actuate said indicating device distinctively from the actuation due to said indication current.

40 5. An interlocking system for railroads

comprising, a source of current, an electrically operated traffic controlling device, a lever of a mechanically interlocked group of levers for controlling said device by alternating current flowing in a main partial circuit, an indicating device connected to said partial circuit when said lever is in a normal or in an indication position, said traffic controlling device including means for energizing said indicating device when the traffic controlling device has been actuated to the proper position by an alternating current in said main partial circuit having substantially the same phase relation with respect to said source as the alternating current derived from said source for controlling said device.

45 6. An interlocking system for railways comprising a lever mechanically interlocked with a group of other levers, a distant traffic controlling device, an induction motor of the usual construction having two field windings and a rotor, an indicating device, means for energizing both of said windings by alternating current to cause said motor to operate as an induction motor and actuate said device to a biased position and for energizing only one of said windings by alternating current and connecting the other of said windings to said indicating device when said traffic controlling device has by its bias been returned substantially to its original position, whereby said indicating device is operated by current generated by the rotation of said rotor in a field of flux produced by the energized field winding when said device has reached its original position.

50 7. An interlocking system for railways comprising a lever mechanically interlocked with a group of other levers, a distant traffic controlling device, an induction motor having two field windings and a rotor, an indicating device for locking said lever, means for connecting said two field windings in multiple to a source of alternating current to cause said motor to operate as an induction motor and actuate said traffic controlling device, or for connecting one of said windings to said source of alternating current and connecting the other winding to said indicating device, whereby said indicating device is actuated by current generated by the rotation of said rotor in the field of flux produced by the energized winding.

55 8. A dynamic indication and cross protection system for railways comprising, a traffic controlling device including a motor, a partial circuit including a main wire, said traffic controlling device and a common return wire, a source of alternating current having one terminal connected to said common return wire, an alternating current indicating device of the polarized type having one terminal connected to said common return wire, a lever adapted to connect said main wire

to said source of alternating current or to said indicating device, and means including said motor effective when said traffic controlling device has reached a predetermined 5 position for generating an alternating current having a phase relation to actuate said indicating device in the reverse direction than it would be actuated if a cross should occur between said main wire and said source 10 of alternating current while said main wire is connected to said indicating device.

9. A dynamic indication and cross protection system according to the preceding claim, further characterized by the provision of 15 means to interrupt the continuity of the common return wire by operation of said indicating device due to such a cross.

10. A dynamic indication and cross protection system for railways comprising, a 20 traffic controlling device, a motor for operating said device, a partial circuit, a lever for connecting said motor to a source of alternating current energy, or to an alternating current polarized indicating device through 25 said partial circuit, and means including said motor for generating an alternating current when said motor has completed a predetermined cycle of operation flowing through said partial circuit and through said 30 indicating device, which is displaced less than ninety electrical degrees with respect to the voltage of said source from the current flowing when said motor is connected to said source, whereby said indicating device 35 facilitates a distinctive indication responsive to a current displaced more than ninety electrical degrees from said operating current.

11. A dynamic indication and cross protection system according to the preceding claim, further characterized by the provision of means to interrupt the continuity of the common return wire by said indicating device when such a distinctive current flows 45 through said indicating device.

12. A dynamic indication and cross protection system for railways comprising, a traffic controlling device including a motor, a partial circuit including a main wire, said 50 traffic controlling device and a common return wire, a source of alternating current having one terminal connected to said common return wire, an alternating current indicating device of the polarized type having 55 one terminal connected to said common return wire, a circuit breaking device in said common return wire governed by said indicating device, a lever adapted to connect said main wire to said source of current or to 60 said indicating device; said polarized alternating current indicating device being so connected in said partial circuit when the

lever is in one position, that an alternating current flowing due to a cross between said main wire and said source will cause said 65 indicating device to actuate said circuit breaking device and break the continuity of said common return wire.

13. In an interlocking system for railways, the combination of a lever, of a mechanically interlocked group of levers, a lock for said lever, a source of alternating current, an indicating device for controlling said lock, a distant traffic controlling device, an induction motor having two field windings and a rotor for operating said traffic controlling device, a common wire for carrying both the current for energizing said motor and the current for actuating said indicating device, and means including 80 said lever which under one condition connects said windings to said source to operate said motor and when in another condition connects one of said windings to said source and the other of said windings to said indicating device in a manner so that the current generated in said other winding due to the field produced by said first mentioned winding and said rotor and flowing in said common wire is substantially in phase opposition 85 to the current flowing in said common wire when said motor windings are connected for operating said motor, said indicating device controlling said lock only when energized by current having a component substantially 90 in phase with the current generated in said other winding.

14. In a manually operated and electrically controlled semaphore signal for railway signalling purposes, the combination of a 100 semaphore blade tending to assume its danger indicating position, means for operating said blade to its clear position and holding it there including an induction motor having two field windings and a rotor, a 105 source of alternating current, a lever which when placed in one position connects both of said windings to said source of current to operate said motor to move said semaphore to the clear position and which if placed in another position allows said semaphore to 110 return to the danger position and connects one of said windings to said source and the other to a suitable indicating device, whereby a current having a distinctive phase relation is generated in said other winding by the rotation of said rotor in the field produced by said energized field winding when the semaphore is returning to the danger 115 indicating position.

In testimony whcreof I hereby affix my signature.

PHILIP X. RICE.
